UNITED STATES PATENT OFFICE.

HOLLIS H. HARRIS, OF LORAIN, OHIO, ASSIGNOR TO THE THEW SHOVEL COMPANY,
OF LORAIN, OHIO, A CORPORATION OF OHIO.

POWER-SHOVEL.

1,393,361.

Specification of Letters Patent. Patented Oct. 11, 1921.

Application filed March 15, 1919. Serial No. 282,929.

To all whom it may concern:

Be it known that I, HOLLIS H. HARRIS, a citizen of the United States, residing at Lorain, in the county of Lorain and State of Ohio, have invented a certain new and useful Improvement in Power-Shovels, of which the following is a full, clear, and exact description, reference being had to the accompanying drawings.

10 This invention relates to steam shovels and the like wherein a dipper and dipper stick are caused to travel with relation to a boom carrying the same and one of the essential objects of the invention is to provide a light, strong and elastic boom construction. Another object of the invention is to provide a novel guiding means for the dipper stick in connection with the boom and mechanism for operating the dipper. 15 20 The invention is more fully described in connection with the accompanying drawings, illustrating a preferred embodiment thereof, the essential characteristics being summarized in the claims.

25 In the drawings, Figure 1 is a side elevation of the steam shovel embodying the present invention; Fig. 2 is an enlarged side elevation of the boom; Fig. 3 is a plan of the same; Fig. 4 is a longitudinal section taken 30 on the plane indicated by the line 4—4 of Fig. 3; Fig. 5 is a similar section taken on a plane parallel with the plane of Fig. 4 indicated by the line 5—5 of Fig. 3; Fig. 6 is an enlarged transverse section through 35 the boom, dipper stick and operating mechanism therefor; Fig. 7 is a transverse section through the boom on the same scale as Fig. 6; taken on a plane indicated by the line 7—7 of Fig. 4; Fig. 8 is a similar section indicated by the line 8—8 of Fig. 4; Fig. 9 is a sectional view showing a swivel guiding connection between the boom and dipper stick and showing the gear and rack connection between the guiding means on 40 the boom and the rack on the dipper stick.

In Fig. 1, is shown a suitable truck 1 on which is swivelly mounted a platform 3, carrying a housing 5 for mechanism for raising and lowering the boom 6 and for 45 rotating the frame 3 on the truck. 7 is a brace rod anchored at one end within the housing and attached to a cross beam 8 on plates 9 at the free end of the boom. The usual dipper 10 is shown as suitably carried on a dipper stick 12, guided through

the boom. A cable 13 extends over a pulley 14 on a shaft 15 at the outer end of the boom, then through a pulley block 16 and over a second pulley on the shaft 15, (arranged beside the pulley 14) and attached 60 at 17 on the pulley block. The pulley block is attached to a bail 18 pivoted at 19 to opposite sides of the dipper. Suitable mechanism (not shown) for drawing upwardly on the dipper by winding the cable 13 is 65 provided inside the housing 5.

In the construction of steam shovels for certain kinds of work, it is desirable to have the boom as light, strong and, particularly, as elastic as possible. I have accordingly 70 devised a novel boom construction, embodying a peculiar arrangement of bracing wood strips and a minimum amount of structural iron or steel. The construction of the boom, as illustrated particularly in Figs. 2 to 8, 75 will now be described.

At 20, 20 are indicated side plates of iron or steel, extending throughout the length of the boom and braced at their upper edges by angle members 21 extending substantially the full length of the plates. At the lower edges are similar angle irons or beams 22 extending from the outer end of the boom to the widest portions thereof adjacent the rear or lower end of the boom. Transverse 80 angle members 23, 24 and 25 are shown as extending between the flanges of the angles 21 and 22 at separated points, thus forming a rigid beam construction. Between the plates 20, 20 at the rear end of the boom I 90 provide a peculiar arrangement of wood preferably in the form of short narrow strips of heavy planking, shown as arranged substantially as follows:

Extending parallel with the upper edges 95 of the plates 20 from the rear ends of the plates forwardly for a few feet is a series of such wood members placed side by side, as indicated at 28, through which bolts 29 extend, securing the plates 20 thereto. This 100 series of strips forms a distance member between the plates at the rear of the boom. The rear lower edges of the strips 28 are chamfered and similar strips 30 extend from the rear portion of the strips 28 and plates 105 20 forwardly along the sloping edge of these plates. I prefer to arrange strips 30 in such fashion as to alternately engage and dove-tail into strips 34 sloping from a point somewhat ahead of the ends of the strips 110

28 downwardly to the widest portion of the plates 20 as shown in Figs. 4 and 5. Between the overlapping strips are shorter strips each cut to abut the upper side of the 5 opposite strip in the same plane. Bolts 33 and 35 extend through the members 30 and 34 respectively. At 36 is shown a single bolt extending through the overlapping portions of these wood members.

10 The boom may be pivotally attached to the frame or platform 3 by suitable brackets 40 preferably comprising offset plate-like members 41 having suitable openings for receiving a transverse shaft or pivot pin on 15 which the boom is supported, and extending along the plates 20 and secured thereto by a bolt 43 passing through both these plates and the forward ends of the brackets. Bracing ribs 44 are shown as leading from 20 a point adjacent the bolt 43 to the rearward portions of the members 41 and suitable webs 45 add to the strength of the bracket by closing the space between the ribs 44 and members 41. Bolts 46 at either side of 25 the ribs 44 pass entirely through both plates 20 and the intermediate wood members 28 and 30.

Near the free outward end of the boom, the plates 20 are spaced apart and braced by 30 an arrangement of wood members somewhat similar to the members 30 and 34 as follows: Members 50 and 52 extend diagonally from the upper edge of the plates substantially to the lower edge. The alternate 35 members overlap with intermediate members, being cut shorter to fit against the upper edges of the longitudinally aligned corresponding members, as described in connection with the strips 30 and 34. Thus a member 50^a extends from the upper edge of the plate 20 to the upper edge of a member 52^a which in turn extends from the upper edge of the plate 20 rearwardly and downwardly to the lower edge thereof. By 40 this construction the strips form a solid distance piece and act as bracing members resisting bending strain on the boom. A bolt 53 passes through the plates 20 and overlapping portions of the members 50 and 52 45 while bolts 54 and 55 pass through the members 50 and 52 respectively.

For the bolts which come just below the angles 21, I prefer to provide rectangular washers 56 overlapping the vertical flanges 55 of the angle members 21, thus adding to the strength of the boom structure at this point. Similar washers are provided for the bolts 29 and 35, for the same purpose.

The arrangement of plates 9 at the outer 60 end of the boom is illustrated clearly in Figs. 2 to 5. The openings indicated at 15^a through the plates 9 and 20 receive the shaft 15.

To additionally strengthen the boom and 65 provide an economical and very satisfactory

guide for the dipper stick I arrange parallel with the lower edges of the plates 20 sections of railroad rails indicated at 60, having their flanges abutting these plates and suitably riveted thereto.

These rails preferably extend from points adjacent plates 9 rearwardly through the overlapping portions of the wood strips 30 and 34, 50 and 52, these strips being cut away (as indicated particularly in Figs. 7 75 and 8) to accommodate these rails. Thus it will be seen that the boom has an intermediate rectangular opening allowing wide angular movement of the dipper stick. The heads of the rails 60 engage and guide the 80 stick and effectively prevent side play.

Along intermediate portions of the boom, I provide additional strips of metal at 62 on the upper faces of the flanges of the angles 21. These strips are suitably riveted 85 to these flanges and at the rear of the strips, preferably above the wood bracing members 34, is a transverse plate 64 riveted to the flanges of the angles 21. This plate provides a suitable base for a small steam engine indicated at 65, which may actuate the 90 dipper stick through suitable gearing.

The driving mechanism for the dipper stick is shown particularly in Figs. 1, 6 and 9. It may conveniently comprise a crank 95 shaft 66, driven by the connecting rod of the engine, and having a pinion 67 meshing with a gear 68 on the shaft 69, extending transversely of the boom and provided at each end with pinions 70, meshing with 100 gears 72 on a shaft 73. The shafts, 69 and 73 are provided with bearings in suitable brackets 74 secured along the strips 62 on the upper side of each structural side frame member. On the intermediate portion of 105 the shaft 72 is a heavy toothed gear 75, meshing with a rack 76, secured to the lower side of the dipper stick, whereby power may be transmitted from the engine to the 110 gearing described to move the dipper stick longitudinally. Between the gear 75 and the bearing brackets 74, the shaft 73 is 115 embraced by bearing members 80 of bracket arms 82, which are connected at their outer ends by transverse cap 84. The inner sides of the bracket arms 82 and cap 84 embrace three sides of the dipper stick while the lower side is supported on the gear 75, thus forming a pivoted swinging guide for the 120 stick, allowing the free swinging movement thereof while providing simple and very positive driving mechanism.

The cable 13, for raising the dipper stick, tends to interfere with the free movement of the dipper stick or associated mechanism. 125 To prevent this, I mount, on one of the bearings 74, a bracket 86 carrying a sheave 88 mounted at an angle to the shaft and boom, as illustrated in Fig. 6. The cable 13 is passed under the lower side of this sheave as 130

shown in Fig. 1, providing a positive guide therefor and deflecting the cable from the path of the stick. This guide is preferably at a point near the pivot of the dipper stick,

5 whereby it need deflect the cable but slightly to clear the stick. The angle of the sheave is such that the deflection of the cable is through the same plane as the sheave itself.

The construction of the dipper stick may 10 be accomplished in a very simple and economical manner by the use of two inwardly facing channel members 90 and a plate 91 secured across the upper flanges of these channels and the rack 76, secured along the 15 lower flanges. This forms a rectangular boxlike structure, rigid in character and readily adaptable to being guided by the guides 82 and rails 60.

It will be seen from the foregoing description, that I have provided a simple and economical boom and dipper constructions. Practice has demonstrated that it is very durable, and the elasticity of the wood prevents the usual wear on the bolts, which 25 may be tightened readily.

Having thus described my invention what I claim is:—

1. In a boom construction, the combination of a pair of structural side frame members, a plurality of wood blocks secured side by side between the side frame members adjacent each end thereof leaving an intermediate opening, guides adapted to embrace a dipper stick, and mounted on the structural side members.

2. In a boom construction, the combination of structural side frame members, a plurality of spacing strips of wood arranged side by side between the side frame members adjacent each end thereof, an inwardly projecting rail on each frame member extending between the strips at the ends and forming a guide adapted to engage a dipper stick.

45 3. A boom construction, comprising structural side frame members, means for spacing the side frame members apart and suitably bracing them to form a rigid structure and a T-head rail section secured to the inner side of a structural frame member and extending longitudinally thereof.

4. The combination in a boom, of structural side frame members, intervening strips of wood mounted side by side between said members adjacent each end thereof, connecting members extending through the side members and through said strips, T-head rail sections mounted on the inner side of the frame members and extending longitudinally thereof between said blocks.

5. A boom for a power shovel, comprising structural side frame members, a plurality of wood members arranged contiguously, and extending diagonally along the side frame members for a considerable dis-

tance near each end of the structural side frame members, and securing means extending through the side frame members and through said wood members.

6. A boom for a power shovel, comprising structural side frame members, intermediate bracing and spacing members comprising a plurality of wood strips arranged side by side and extending diagonally of the side frame members and between them, 75 said strips being arranged so that the ends of alternate strips dove-tail together.

7. A boom for a power shovel, comprising structural side frame members, intermediate bracing members comprising sets of wood 80 strips arranged side by side and extending diagonally of the side frame members and between them, said strips being arranged so that the ends of alternate strips dove-tail together and form an open V, and intermediate strips between the dove-tailed strips each abutting the upper edge of the corresponding strip in the same plane.

8. A boom for a power shovel, comprising structural side frame members spaced 90 apart by a plurality of wood strips, said strips being arranged diagonally of the side frame members and in sets, one set of such strips forming an angle with the other set, strips of the one set overlapping the ends 95 of strips of the other set, intermediate strips between the overlapping strips each extending to and abutting the near side of the corresponding overlapping strip in the same plane.

9. A boom for a power shovel comprising structural side frame members spaced apart by a plurality of wood strips, said strips being arranged diagonally of the side frame members and in sets, strips of the one set 105 overlapping the ends of strips of the other set, and a bolt through the overlapping portion thereof and through the side members.

10. A boom for a power shovel, comprising a pair of structural side frame members, 110 and a plurality of strips of wood between the side frame members adjacent the rear end of the boom, said strips being contiguously arranged in sets, one set extending longitudinally of the boom and another set 115 extending from the longitudinal set diagonally of the side frame members, a third set of strips extending between and some of the strips of which overlap the strips of the second named set and form an angle therewith.

11. A boom for a power shovel, having structural side frame members and intermediate spacing members, the side frame members comprising plates braced by angle members along its edges, wood spacing members between the plates, bolts through the plates and spacing members and washers for the bolts extending over and engaging one flange of the angle member on each plate.

12. In a boom construction, the combination of a pair of structural side frame members, spacing means between said members, T-head guide rails extending along the inner sides of said structural members and adapted to embrace a dipper stick, transverse members connecting the boom and forming an engine platform, a dipper, a dipper stick engaging the heads of said rails, 10 and means for actuating the dipper stick driven by said engine.
13. In a boom construction, the combination of a pair of structural side frame members, spacing means between said members, 15 guide rails in the form of railroad rails extending along the inner sides of said structural members and adapted to embrace a dipper stick, an engine supported by the boom, a dipper, a dipper stick therefor 20 slidably engaging such rails, and gearing for actuating the dipper stick driven by said engine.
14. The combination with a boom, a dipper stick extending therethrough a dipper 25 carried thereby, pulleys carried by the boom,
- a flexible member for operating the dipper, guide pulleys on the boom and attached to the dipper over which said flexible member may run, means for drawing on said cable at the rear of the boom, and means for deflecting the cable to avoid the dipper stick comprising a bracket and sheave mounted on the boom adjacent the dipper stick. 30
15. In a power shovel, the combination of a boom, a cable extending to the upper end 35 thereof, and normally above the boom, a dipper stick extending through the boom, means for operating the dipper stick carried by the boom, including a swivel guide for the dipper stick, and gearing connected 40 with the dipper stick adjacent the guide, and means for deflecting the cable from the path of the dipper stick comprising a pulley mounted adjacent to said guide and sloped upwardly and inwardly and adapted to be 45 engaged at the under side by the cable.

In testimony whereof I hereunto affix my signature.

HOLLIS H. HARRIS.
